UNITED STATES PATENT OFFICE.

HOWARD S. EVANS, OF PITTSBURGH, PENNSYLVANIA, ASSIGNOR TO MACBETH-EVANS
GLASS COMPANY, OF PITTSBURGH, PENNSYLVANIA, A CORPORATION OF PENN-SYLVANIA.

DESIGN FOR A LAMP-SHADE.

43,526.

Specification for Design.

Patented Feb. 11, 1913.

Application filed December 14, 1912. Serial No. 736,848. Term of patent 14 years.

To all whom it may concern:

Be it known that I, HOWARD S. EVANS, a citizen of the United States, residing at Pittsburgh, in the county of Allegheny and State of Pennsylvania, have invented a new, original, and ornamental Design for Lamp-Shades, of which the following is a specification, reference being had to the accompanying drawing, forming part thereof.

I claim:

The ornamental design for a lamp shade as shown.

HOWARD S. EVANS.

Witnesses:

H. L. LISSFELT,
E. R. COCHRAN.
